UNITED STATES PATENT OFFICE

STEPHEN G. GERLACH, JR., OF HARTFORD, CONNECTICUT

VOCALIZING MUFFLER

Application filed January 13, 1928. Serial No. 246,593.

My invention relates to a device for muffling vocal sounds, and an object of my invention, among others, is to provide a muffler which may be readily adapted for use to 5 muffle vocal sounds while, at the same time, permitting free use of the vocal organs.

One form of device embodying my invention and in the construction and use of which the objects herein set out, as well as others, 10 may be obtained, is illustrated in the accompanying drawings in which—

Figure 1 is a side view of my improved muffler illustrating its manner of use.

Figure 2 is a view in central lengthwise 15 section through the same.

Figure 3 is a view in elevation looking from a point located at right angles from the point of view of Figure 1.

Figure 4 is a view in cross section on the 20 plane denoted by the dotted line 4—4 of Figure 3.

In the accompanying drawings the numeral 5 indicates the case or shell of my improved muffler which is of tubular form and which 25 may be of any suitable shape in cross section, that herein shown being more or less rectangular in this respect. This case comprises a muffler section 6 having an outlet 7 and a mouthpiece 8 preferably located at an angle 30 to the section 6 and having an inlet chamber 9. This mouthpiece may be shaped to fit about the mouth and face of the user, as shown in Fig. 1, and the chamber 9 will be of such size as to permit substantially a full 35 volume of vocal sounds.

Within the case and preferably in the section 6 I provide barriers 10 that are preferably of A shape, as shown in Fig. 3, these barriers being arranged on opposite sides 40 of the chamber in the section 6 in staggered relation and projecting toward the longitudinal section of the center, but preferably terminating short of such center or axis. Any suitable number of these barriers may be employed.

In addition to the barriers 10 I also provide baffles 11 extending toward the center of the case from opposite walls and in a direction substantially at right angles to that in 50 which the barriers 10 extend. These baffles

11 are preferably arranged at substantially right angles to the wall of the case and the baffles from opposite walls project toward each other and into the space between the barriers 10. The outer edges of the baffles 55 preferably terminate short of the longitudinal center of the case and as shown in Fig. 3 and Fig. 4 of the drawings. The mouth or outlet 7 is preferably reduced in size.

If desired a stand or support for the muffler 60 may be provided, this comprising a base 12 having a standard or post 13 rising therefrom and with its upper end passed into a hole in a lug 14 on the side of the case. A set screw 15 may be employed to secure the post 13 65 within the lug.

It will be noted that this structure provides a means whereby the vocal sounds produced by a person in the act of practicing singing may be effectually subdued, the 70 sounds passing into the case and being effectually broken up by contact with the barriers and baffles that cause such sounds to pass in a devious course through the case and the sound currents being divided and broken up 75 so that but little sound will be perceptible at little distance from the muffler.

In accordance with the provisions of the patent statutes I have described the principles of operation of my invention, together 80 with the device which I now consider to represent the best embodiment thereof, but I desire to have it understood that the device shown is only illustrative and that the invention may be carried out by other means 85 and applied to uses other than those above set out.

I claim—

1. A vocalizing muffler including a case of tubular form having a mouthpiece at one end 90 within which the mouth and part of the face of a person may be placed, said case also having an outlet, barriers projecting from opposite walls of the case toward each other with a space between them, and baffles different in 95 shape from the barriers and extending from opposite walls of the case with a space between them.

2. A vocalizing muffler for materially reducing said volume including a case of tubu- 100

lar form having a mouthpiece at one end and a muffler section through which all of the sound must pass arranged at an angle to the mouthpiece with an outlet therefrom, and means within the muffler section for effecting a devious course of sound waves therein from the mouthpiece to the outlet.

5 3. A vocalizing muffler including a case of tubular form having a mouthpiece at one end and an outlet at the opposite end, barriers of angular form in section projecting from opposite walls of the case in staggered relation, and baffles projecting from opposite walls of the case into the interior thereof at substantially right angles to the barriers.

10 4. A vocalizing muffler including a case of tubular form and embodying a mouthpiece, and a muffler section located at an angle to said mouthpiece, and barriers of angular shape in section projecting from opposite walls of the case in staggered relation.

15 5. A vocalizing muffler including a case of tubular form having a mouthpiece at one end and an outlet at the opposite end, barriers of angular shape in section projecting from opposite walls of the case in staggered relation, and baffles projecting from opposite walls of the case at right angles to said barriers, said baffles being located between said barriers.

20 6. A vocalizing muffler including a case of tubular form having a mouthpiece at one end and an outlet at the opposite end, barriers of angular shape in section projecting from opposite walls of the case in staggered relation and terminating short of the longitudinal center thereof, and baffles projecting from opposite walls of the case at right angles to said barriers and into the space between the barriers and terminating short of the longitudinal center thereof, thereby creating a clear opening through the case.

25 7. A vocalizing muffler for materially reducing sound volume including a tubular casing having a horizontally opening mouthpiece within which the mouth and part of the face of a person may be placed, said muffler also including a perpendicular muffler section, a vertical support, and means for 30 vertically adjustably mounting the casing upon said support.
